7 Claims. (Cl. 112—2)

The present invention relates to sewing machines. More particularly, the present invention relates to a spiral stitching mechanism for sewing machines.

The spiral stitching mechanism of the present invention serves to stitch fabrics with a continuous spiral seam and is specifically adapted to stitch generally hemispherically constructed forms of work such as, for example, brassiere cups. The mechanism of the present invention serves to produce a spiraling continuous line of stitching on the hemispherical cup which serves to reinforce and stiffen the cup.

The spiral stitching mechanism of the present invention is combined with a conventional sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power.

A conventional sewing machine may be facilely adapted to sew spiral seams on fabrics of various types and qualities by the utilization of the spiral stitching mechanism of the present invention. The spacing between the consecutive convolutions of the spiral seam sewn by the mechanism of the present invention may be readily adjusted.

In accordance with the present invention, the spiral stitching mechanism effects lateral movement of a workpiece relative to the stitching mechanism at a varying rate thereby to produce spiral stitching, by translating the rotation of a shaft driven by the power source into such lateral movement. The translation of the rotation of the power shaft into a varying lateral motion is provided by a gear segment driven by the power source and a connecting arm or loss bar pivoted on the gear segment at one end and adapted to move freely along the edge of a lateral pressure bar at the other end, the work bar being coupled to said other end of said loss bar.

The principal object of the present invention is to provide a spiral stitching mechanism for producing a spiral seam having uniformly spaced consecutive convolutions.

Another object of the invention is the provision of a spiral stitching mechanism for producing a spiral seam having uniformly spaced consecutive convolutions the spacing of which may be varied as desired.

Another object of the invention is the provision of a spiral stitching mechanism which may be facilely installed in a conventional sewing machine.

Another object of the invention is the provision of a spiral stitching mechanism which may be readily installed in a conventional sewing machine with no waste of space whatever.

Another object of the invention is the provision of a spiral stitching mechanism which may be readily installed in a conventional sewing machine in a manner whereby oil drippings from the machine are utilized to lubricate the mechanism.

Another object of the invention is the provision of a spiral stitching mechanism which is of relatively simple configuration.

Another object of the invention is the provision of a spiral stitching mechanism which comprises relatively few parts.

Another object of the invention is the provision of a spiral stitching mechanism which is of rugged and durable construction.

Another object of the invention is the provision of a spiral stitching mechanism which is instantly and easily retractable.

Still another object of the invention is the provision of a spiral stitching mechanism which is relatively inexpensive to manufacture and which costs virtually nothing to maintain.

These and other objects and features of the invention will be apparent from a consideration of the following detailed description taken in connection with the accompanying drawing, wherein:

FIG. 1 is a schematic diagram, partly in section, of an embodiment of the spiral stitching mechanism of the present invention;

FIG. 2 is a schematic diagram, partly in section, of a portion of the embodiment of the spiral stitching mechanism of FIG. 1, a portion of FIG. 2 being taken along the line 2—2 of FIG. 1; and

FIG. 3 is a schematic diagram, partly in section, of another portion of the embodiment of FIG. 1, a portion of FIG. 3 being taken along the line 3—3 of FIG. 1.

FIG. 4 is a detailed elevation view, partly in section, illustrating the coupling of the work bar to the work plate of the mechanism.

In FIG. 1, the invention is illustrated in the form of a unit which may be easily attached to a conventional sewing machine whereby such machine, without alteration or delay, may be readily converted to a machine for providing spiral stitching. The main elements of the invention are supported in a housing 1 having a bottom portion 2 and sides 3, 4, 5 and 6. The housing 1 is preferably provided with fastening means for affixing said housing to a sewing machine in place of the conventionally used oil pan. Suitable fastening means may comprise, for example, apertured ears 7, 8, 9 and 10 through which the housing 1 may be fastened by screws to the under surface of a sewing machine work surface in the area formerly occupied by the oil pan in a manner whereby said housing is supported in a substantially horizontal position with the bottom portion 2 down.

A variable speed pulley 11 is driven by the power source of the machine in any suitable manner known in the art and rotates a shaft 12 to which it is affixed at a speed which may be varied by variation of the speed of the power source in any suitable manner known in the art.

The shaft 12 is connected in a gear box 13 to continuously drive a master gear (not shown). The gear box 13 comprises any suitable gear coupling means known in the art for translating the rotary motion of the shaft 12 to a rotary motion of the master gear in a plane substantially perpendicular to the plane of rotation of said shaft.

A pinion 14 extends from the top of the gear box 13 and is adapted to be driven by the master gear. When so driven, the pinion 14 rotates about its axis 15. The gear box 13 further comprises any suitable clutch means known in the art for driving the pinion 14 with the master gear when said clutch means is engaged and for permitting free rotation of said pinion when said clutch means is disengaged. The clutch means included in the gear box 13 is operated manually through a control rod (not shown) extending from said gear box. In the course of normal operation of the machine, the clutch is engaged and the pinion 14 is driven by the master gear of the gear box 13 to rotate about its axis 15 at a substantially constant speed.

In a preferred embodiment of the invention, the gear

box 13 is so positioned in the bottom portion 2 of the housing 1 that the pinion 14 is substantially parallel to said bottom portion in a substantially horizontal plane which is located at a small distance above the said bottom portion whereas the bulk of said gear box including the shaft 12 and pulley 11 are located below the said bottom portion outside said housing.

The pinion 14 rotates about the axis 15 in the direction indicated by an arrow "a" and engages a gear segment or pivoting element 16 in a manner whereby it drives said gear segment at a substantially constant rate in the direction indicated by an arrow "b." The gear segment 16 is supported by a pivot pin 17 and is adapted to rotate about said pivot pin. That is, the gear segment 16 describes a substantially arcuate motion. The pivot pin 17 (FIG. 2) is affixed substantially vertically to the bottom portion 2 of the housing 1 and supports the gear segment 16 in a substantially horizontal plane located at a small distance above said bottom portion. The gear segment or pivoting element 16 may be of any suitable configuration, of course; the form illustrated having been selected because it occupies a minimum of space.

A connecting arm or loss bar 18 is positioned in a substantially horizontal plane slightly above the plane of the gear segment 16. The loss bar 18 is pivotally coupled at one end to the upper surface of the gear segment 16 through a pivot pin 19 about which said loss bar is freely rotatable.

The other end of the loss bar 18 is affixed to a plate 20 which is preferably positioned below said loss bar in a manner whereby there is no interference between the gear segment 16 and said plate at any position of either. A ball bearing 21 is affixed to the plate 20 in a manner whereby it is freely rotatable about its axis 22. The ball bearing 21 is adapted to roll along a substantially lateral edge 23 of a lateral pressure bar 24. The lateral pressure bar 24 is affixed to the bottom portion 2 of the housing 1 in a manner whereby said lateral pressure bar is positioned in a substantially horizontal plane at a distance above said bottom portion sufficient to permit the free movement of the gear segment 16 and the plate 20 between the bottom surface of the said pressure bar and the upper surface of said bottom portion in any position of said gear segment and said plate. The lateral pressure bar 24 is positioned to present the edge 23 thereof in the lateral direction relative to the direction of forward feed produced by the stitching means of the sewing machine as previously defined.

As a result of the unique coupling arrangement of the present invention the ball bearing 21 moves in a lateral direction along the edge 23 of the lateral pressure bar 24 indicated by an arrow "c" at a varying rate which is a maximum when said bearing is at its farthest right-hand position and which is a minimum when said bearing is at its farthest left-hand position. The pivot 19 area of the loss bar 18 moves in a direction generally indicated by an arrow "d."

In FIG. 2 a work bar 25, not shown in FIG. 1 to prevent complication of the drawing and thereby aid in the clarity of the illustration, is supported by any suitable means known in the art for permitting free movement thereof in a lateral direction relative to the direction of forward feed of the sewing machine, as previously described. Suitable supporting means may comprise, for example, ball bearing means 26 and 27; the ball bearing means 26 being supported in an aperture in the side 3 of the housing 1. Any suitable coupling means known in the art may be utilized to couple the work bar 25 to the loss bar 18 in a manner whereby said work bar moves conjointly with the ball bearing 21. Suitable coupling means may comprise, for example, a pin 28 supported on the plate 20 coaxially with the axis 22 of the ball bearing 21 and fitting in a substantially vertical aperture through the work bar 25. In a preferred embodiment of the invention, the ball bearing 21 may be covered by a

5 second plate 29 which is positioned parallel to the first plate 29 and spaced from said first plate so that it may move freely over the upper surface of the lateral pressure bar 24; the ball bearing 21 being freely rotatable about its axis 22 and moving along the lateral edge 23 of said lateral pressure bar. The pin 28 may be affixed to the upper plate 29 and fitted in a substantially vertical hole through the work bar 25. As seen in FIG. 4, the pin 28 is further secured to work plate 36. The work plate 10 36 is provided with a work-engaging needle 38 upon which the brassiere cup C is mounted. A sewing machine 40 is adapted to perform the spiral stitching on the cup C.

15 The lateral motion at a varying rate of the work bar 25 may be translated to the spiral stitching of a workpiece by any suitable coupling means between said work bar and the work plate of the sewing machine known in the art. Such a structure for coupling the present mechanism to a work plate of a sewing machine is clearly shown in our 20 co-pending U.S. patent application, Serial No. 635,215, filed January 22, 1957, now Patent No. 2,955,551, and entitled "Spiral Stitching Device for Sewing Machines." The coupling of the work bar 25 to the work plate of the machine is through a slot in the working surface of the 25 machine since the spiral stitching mechanism of the present invention is positioned beneath said working surface as previously described. Suitable work bar to work plate coupling means may comprise a pivot pin coupling said work bar and work plate in a manner whereby the workpiece, which may be pivoted on said work plate, is moved away from the stitching means of the sewing machine laterally relative to the direction of forward feed produced by said stitching means at a varying rate which 30 decreases from an initial maximum value whereby a spiral seam is sewn in said workpiece.

35 The spiral seam produced by the mechanism of the present invention has uniformly spaced consecutive convolutions due to the varying rate of lateral motion of the work bar 25. The spacing of these convolutions may be varied as desired by varying the speed of the pulley 11 by any suitable means known in the art. Thus, at a relatively low pulley 11 speed, the lateral motion of the work bar 25 varies at a relatively slow rate and the consecutive convolutions are relatively closely spaced; whereas, at a relatively high pulley 11 speed, the lateral motion of the work bar 25 varies at a relatively fast rate and the consecutive convolutions are relatively widely spaced.

40 The spiral stitching mechanism of the present invention is instantly and easily retractible by manual operation of the clutch control rod (not shown) extending from the gear box 13 to disengage the clutch. When the clutch is disengaged the pinion 14 and the gear segment 16 are freely rotatable about the axis 15 and pivot 19, respectively, so that the work bar 25 may be manually 45 returned to its farthest right-hand position thereby moving the ball bearing 21 back to its farthest right-hand position and moving the gear segment 16 to its "start" position. In the "start" position, the pivot pin 19 is at a maximum distance from the wall 4 of the housing 1 and the pin 28 is at its farthest right-hand position at its maximum distance from the wall 3 of said housing. When the clutch is engaged, the operation is instituted as described. At the termination of the operation, before the disengaging of the clutch, when the mechanism is 50 in its "stop" position, the pin 28, ball bearing 21 and work bar 25 are at their farthest left-hand positions at a minimum distance from the wall 3 of the housing 1 and pivot pin 19 is at a minimum distance from the wall 4 of said housing.

55 A suitable type of clutch arrangement which may be utilized in the gear box 13 may comprise, for example, a friction type clutch of the type shown in FIG. 3, where- 60 in the axis of the pinion 14 is the axis of the shaft 30. A driven gear 31 is affixed to the shaft 30 and is adapted to rotate said shaft thereby to rotate the pinion 14,

which is also affixed to said shaft. A master drive gear 32 is continuously rotated about the axis 15 by the power source (not shown) through the pulley 11 by any suitable means known in the art. The master drive gear 32 is not affixed to the shaft 30 but may be affixed, for example, to a shaft 33 which is coaxial with the shaft 30 and of a diameter which is sufficiently larger than the diameter of said shaft 30 to permit free rotation and axial movement of the said shaft 30.

When the clutch arrangement is engaged, the driven gear 31 is in frictional engagement with the master drive gear 32 and rotates the shaft 30 and the pinion 14 affixed to said shaft. To disengage the clutch, the manually operated control rod (not shown) extending from the gear box 13 is moved to disengage the driven gear 31 from the master drive gear 32. The disengagement of the gears 31 and 32 may be accomplished by any suitable means known in the art for moving the shaft 30 upward in the direction of an arrow "e." When the shaft 30 is moved upward a sufficient distance in the direction of the arrow "e" the driven gear 31 is moved out of frictional engagement with the master drive gear 32 and the pinion 14 and the gear segment 16 are freely rotatable about the axis 15 and pivot 19, respectively; said driven gear being freely rotatable about said axis.

In accordance with another feature of the present invention, the clutch arrangement is automatically disengaged to prevent stripping of the gears in the event that the mechanism is permitted to run to its mechanical limit. The automatic disengagement of the clutch thus functions as a safety stop for the spiral stitching mechanism of the present invention. The automatic safety stop comprises a substantially wedge shaped member 34 affixed to the gear segment 16 in a position whereby said member is adapted to engage the under surface of an annular head 35 affixed substantially coaxially to the shaft 30. The member 34 and the head 35 are so positioned that when the gear segment 16 nears the position that it acquires at the termination of the operation, and is moving in the direction of the arrow "b," the upper surface of the member 34 engages the under surface of the head 35. As the gear segment 16 continues to move in the direction of the arrow "b" the member 34 lifts the head 35, by reason of the inclined upper surface of said member, and thereby moves the shaft 30 upward in the direction of the arrow "e." The incline of the upper surface of the member 34 is sufficient to move the shaft 30 upward a distance sufficient to disengage the driven gear 31 from the master drive gear 32 and thereby disengage the clutch arrangement. This permits free rotation of the pinion 14, the driven gear 31 and the gear segment 16 and prevents stripping of the gears of the gear box 13 and of said pinion and gear segment.

While the invention has been described by means of a specific example and in a specific embodiment, we do not wish to be limited thereto, for obvious modifications will occur to those skilled in the art without departing from the spirit and scope of the invention.

What we claim is:

1. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power, of means for moving said work bar at a varying rate whereby said stitching means produces a seam in the form of a spiral in said workpiece, said last-mentioned means comprising a pivoting element, means for driving said pivoting element from said source of power, said power source including clutch means for disengaging said driving of said pivoting element thereby permitting free rotation of said

pivoting element, means mounted on said pivoting element for automatically disengaging said clutch means at a predetermined position of the said pivoting element, a loss bar pivotally coupled at one end to said pivoting element, means guiding the other end of said loss bar in said lateral direction in a manner whereby said other end of the said loss bar moves at a varying rate in the said lateral direction, and means coupling said other end of said loss bar to said work bar in a manner whereby the said work bar moves conjointly with the said other end of said loss bar.

2. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means, and a source of power, means for moving said work bar at a varying rate whereby said stitching means produces a seam in the form of a spiral in said workpiece, said last-mentioned means comprising a pivoting element, means for driving said pivoting element at a substantially constant rate from said source of power, a loss bar pivotally coupled at one-end to said pivoting element, means guiding the other end of said loss bar in said lateral direction in a manner whereby said other end of the said loss bar moves at a varying rate in the said lateral direction, said rate decreasing from an initial maximum value, and means coupling said other end of said loss bar to said work bar in a manner whereby the said work bar moves conjointly with the said other end of said loss bar.

3. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power, of means for moving said work bar at a varying rate whereby said stitching means produces a seam in the form of a spiral in said workpiece, said last-mentioned means comprising a gear segment, means for driving said gear segment at a substantially constant rate from said source of power, a loss bar pivotally coupled at one end to said gear segment, a lateral pressure bar positioned whereby an edge thereof extends in said lateral direction, means guiding the other end of said loss bar along said edge of said pressure bar in a manner whereby said other end of the said loss bar moves at a varying rate in the said lateral direction, said rate decreasing from an initial maximum value, and means coupling said other end of said loss bar to said work bar in a manner whereby the said work bar moves conjointly with the said other end of said loss bar.

4. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power, of means for moving said work bar at a varying rate whereby said stitching means produces a seam in the form of a spiral in said workpiece, said last-mentioned means comprising a gear segment, means for driving said gear segment at a substantially constant rate from said source of power, a loss bar pivotally coupled at one end to said gear segment, a lateral pressure bar positioned to present an edge thereof in said lateral direction, ball bearing means guiding the other end of said loss bar along said edge of said pressure bar in a manner whereby said other end of the

said loss bar moves at a varying rate in the said lateral direction, said rate decreasing from an initial maximum value, and means coupling said other end of said loss bar to said work bar in a manner whereby the said work bar moves conjointly with the said other end of said loss bar.

5. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means, and a source of power, means for moving said work bar at a varying rate whereby said stitching means produces a seam in the form of a spiral in said workpiece, said last-mentioned means comprising pivoting element means for driving said pivoting element at a substantially constant rate from said source of power, a loss bar pivotally coupled at one end to said pivoting element, a lateral pressure bar positioned whereby an edge thereof extends in said lateral direction, ball bearing means guiding the other end of said loss bar along said edge of said pressure bar in a manner whereby said other end of said loss bar moves at a varying rate in the said lateral direction, said rate decreasing from an initial maximum value, and means pivotally coupling said other end of said loss bar to said work bar in a manner whereby the said work bar moves conjointly with the said other end of said loss bar.

6. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power, of means for moving said work bar at a varying rate whereby said stitching means produces a seam in the form of a spiral in said workpiece, said last-mentioned means comprising a gear segment, means for driving said gear segment at a substantially constant rate from said source of power, a loss bar pivotally coupled at one end to said gear segment, a lateral pressure bar positioned to present an edge thereof in said lateral direction, ball bearing means supported at the other end of said loss bar guiding said other end of said loss bar along said edge of said pressure bar in a manner whereby the said other end of said loss bar moves at a varying rate in the said lateral direction, said rate decreasing from an initial maximum value, and means pivotally coupling said other end of said loss bar to said work bar in a manner whereby the said work bar moves conjointly with the said other end of said loss bar, said last-mentioned means comprising a pin affixed to said

other end of said loss bar substantially coaxially with said ball bearing means and adapted to fit in an aperture through said work bar.

7. The combination with a sewing machine having stitching means, a work plate provided with means adjacent said stitching means for pivotally supporting a workpiece thereon, a work bar, means coupling said work bar to said work plate in a manner whereby said workpiece is adapted to be moved by said work bar laterally relative to the direction of forward feed produced by said stitching means and a source of power, of means for moving said work bar at a varying rate whereby said stitching means produces a seam in the form of a spiral in said workpiece, said last-mentioned means comprising a gear segment, means for driving said gear segment at a substantially constant rate from said source of power, said power source including a pinion for driving said gear segment and clutch means for disengaging said pinion from said gear segment thereby permitting free rotation of the said gear segment, means for automatically disengaging said clutch means at a predetermined position of said gear segment, said last-mentioned means comprising a head member coaxially mounted on said pinion and a substantially wedge shaped member mounted on said gear segment and adapted to coat with said head member to lift said pinion vertically out of engagement with the said gear segment upon a predetermined transverse of said gear segment in one direction, a loss bar pivotally coupled at one end to said gear segment, a lateral pressure bar positioned whereby an edge thereof extends in said lateral direction, means supported at the other end of said loss bar guiding said other end of said loss bar along said edge of said pressure bar in a manner whereby the said other end of said loss bar moves at a varying rate in the said lateral direction, said rate decreasing from an initial maximum value, and means pivotally coupling said other end of said loss bar to said work bar in a manner whereby the said work bar moves conjointly with the said other end of said loss bar.
